UNITED STATES PATENT OFFICE.

MILTON GUSTAVE LANGE, OF NEW YORK, N. Y., ASSIGNOR TO EFFECTIVE ADVERTISING COMPANY, INC., OF NEW YORK, N. Y., A CORPORATION OF NEW YORK.

CALENDAR ADVERTISING DEVICE.

1,203,015.

Specification of Letters Patent. Patented Oct. 31, 1916.

Application filed October 29, 1915. Serial No. 58,522.

To all whom it may concern:

Be it known that I, MILTON GUSTAVE LANGE, a citizen of the United States, and resident of the borough of Brooklyn, county 5 of Kings, city and State of New York, have invented certain new and useful Improvements in Calendar Advertising Devices, of which the following is a specification.

This device is intended to be received 10 upon and supported by the transmitter of a telephone and has for its principal objects, the provision of a calendar and advertising matter, together with surfaces adapted to receive memoranda or other data 15 in a position where it will be most readily accessible.

My particular object is to provide such a device and support it in a manner that will make it more attractive and far more 20 convenient for use.

I provide a rigid support for my device and also means for retaining the device in a predetermined position and yet the construction is such that the device or certain 25 parts thereof may be readily rotated so as to bring them out of the normal and into any other desirable location.

The construction of my device and its advantages will be fully set forth as the specification progresses.

The following is what I consider a good means of carrying out my invention and the accompanying drawing forms a part of the specification, in which—

35 Figure 1 shows a simple device in operative position. Fig. 2 shows a duplex construction having certain advantages. Fig. 3 is a section on the line 3—3 in Fig. 2. Fig. 4 shows a modification of the construction 40 shown in Figs. 2 and 3.

Similar reference numerals indicate like parts in all the figures where they appear.

At 1, I have shown a portion of the casting of a transmitter and at 2 a bead or projection from the cover of the transmitter. 45 These parts are of ordinary construction and are fully understood; therefore require no description. Upon the transmitter I engage a clip which may be of metal or any 50 other suitable material and which is made in the shape of a non-complete ring, a portion being omitted between the ends 3 and 4 of the clip. This clip is formed with a right angled bend or inwardly projecting flange 5 and under this flange, I may pro-

vide a plurality of inward projections 6. The clip is also provided with an angular recess 7 extending throughout the entire circumference of the clip and at a point away from the flange 5. Beyond the recess 7, the 60 clip may continue inward to any desirable extent, but it is not necessary that it be carried beyond a distance sufficient to obtain a fair bearing upon the casing of the transmitter. Within the clip and between the flange 5 and projection 6, I place a disk 8 of paper, celluloid, or any other desirable material upon which I may print a calendar and advertising matter as shown in Fig. 1, and it will be noted that the position of the recess 7 allows the disk 8 to present a flat surface. When a calendar and advertising matter are thus presented, it is obvious that certain useful results will be accomplished, but there are other features of my invention 75 that are of equal or greater importance. These features are shown in the remaining figures.

In Fig. 2, two disks are placed within the clip and between the flange 5 and projection 6. The outer disk should be provided with an aperture 10 and upon the inner disk I produce a calendar and other matter, certain sections of which may be observed through the aperture 10, when the inner disk 11 is properly positioned. The outer disk 9 should be constructed of celluloid or other similar material, but the inner disk may be of paper and I call attention to the fact that where a portion of the metallic 90 clip is omitted between the ends 3 and 4, the periphery of the inner disk projects beyond the periphery of the outer disk. In this manner the inner disk may be rotated. Although the disks 9 and 11 are received 95 under the metallic clip or ring, they are not entirely supported thereby. Each is presented with a central perforation through which the mouth piece 1^a of the transmitter may be partly passed and it is the mouth 100 piece that supports the disks and allows the inner disk 11 to be rotated.

I have previously stated that a calendar may be printed upon the inner disk, but to add to the attractiveness and efficiency of my device, I prefer that a space be allowed for special notices which should be printed adjacent to the calendar, and I also prefer that the aperture 10 in the outer disk be sufficiently large to allow such notices to be 110

observed when the calendar is in position for use.

The advantages of my device reside in the construction which provides liberal space 5 for memoranda and other notations, and also in the fact that the device though readily attached is firmly supported in a flat easy reading position, and that even in a device so small liberal space is provided for 10 such advertising matter or display matter as may be desired.

In Fig. 4, I indicate that the monthly section 15 may be removed as a whole and a new section substituted. For some reasons 15 and under some conditions this construction may be preferred. It is obvious, however, that the calendar disk 11 may be removed when no longer desired, or that the calendar disk 8 shown in Fig. 1 may be removed and 20 discarded when another disk is provided to be received into the metallic clip.

Further modifications may be made within 25 the scope of the appended claims without departing from the principle or sacrificing the advantages of the invention.

Having carefully and fully described my invention, what I claim and desire to secure by Letters Patent is—

1. A device of the character described having 30 a resilient metallic member comprising a non-completed ring, a disk received and

rotatable therein and having a number of defined spaces as and for the purpose set forth.

2. A device of the character described 35 having a resilient metallic clip comprising a non-completed ring, adapted to be engaged upon the transmitter of a telephone, a disk retained therein and having an aperture and a second disk arranged interior to the first 40 mentioned disk and having a plurality of defined spaces, said second disk being adapted to be rotated to cause said spaces to register with said aperture as and for the purpose set forth. 45

3. A device of the character described having a resilient clip comprising a non-complete ring and a disk having an aperture, said clip being provided with a plurality of projections and an inwardly extending flange adapted to receive said disk between them and a calendar member adapted to be exposed through said aperture all combined for joint operation as herein specified. 50

Signed at New York city, county and 55 State of New York, this 19th day of Oct., 1915, in the presence of two witnesses.

MILTON GUSTAVE LANGE.
